(57) **CLAIM**

The ornamental design for a plate, as shown and described.

DESCRIPTION

FIG. 1 is a top perspective view of a plate showing my new design;

FIG. 2 is a bottom perspective view thereof;

FIG. 3 is a front view thereof, the left side view being identical thereto, and the rear and right side views being mirror images thereof;

FIG. 4 is a top view thereof; and,

FIG. 5 is a bottom view thereof.

The shade lines in the Figures show contour and not surface ornamentation.
